UNITED STATES PATENT OFFICE.

ENOCH BARNUM, OF KANSAS CITY, MISSOURI.

DUPLEX HEATER.

SPECIFICATION forming part of Letters Patent No. 761,869, dated June 7, 1904.

Application filed December 15, 1903. Serial No. 185,230. (No model.)

To all whom it may concern:

Be it known that I, ENOCH BARNUM, a citizen of the United States, residing at Kansas City, in the county of Jackson and State of Missouri, have invented certain new and useful Improvements in Duplex Heaters, of which the following is a specification.

My invention relates to improvements in heating-drums and means for removing soot therefrom; and my object is to provide means for utilizing a large percentage of the heat which usually escapes through the chimney.

Ordinarily heating-drums are not a success when used in connection with coal-burning stoves, for the reason that they become coated with soot, which being a non-conductor of heat prevents effective radiation of the heat from the interior of the drum to the air in the compartment containing the same.

The invention consists in the novel construction, arrangement, and combination of parts hereinafter described, and pointed out in the claims.

In the accompanying drawings, which illustrate the invention, Figure 1 represents a vertical sectional view of the apparatus connected to a stove, located in a lower compartment. Fig. 2 is a vertical section of the apparatus, taken on line II II of Fig. 1. Fig. 3 is a plan view of the same with the lid removed from the outer casing. Fig. 4 is a vertical section of a modified form, showing the apparatus provided with means for operating the inner drum without disconnecting the outer casing from the outlet-pipe.

In carrying out the invention I employ an outer casing 1, comprising a cylindrical wall 2, a conical-form bottom 3, provided at its lower end with a collar 4, and a lid 5, provided with a centrally-disposed collar 6 and a depending flange 7, which latter fits down snugly over the upper portion of the wall 2 to prevent the escape of smoke or other products of combustion into the compartment containing the apparatus. Casing 1 is mounted upon a plurality of tapering sheet-metal supporting-legs 8, which support it above the floor, so collar 4 may be readily connected to a pipe 9, communicating at its lower end with a heating

stove or furnace 10. Collar 6 is connected to a pipe 11, which conducts the smoke from casing 1 to the chimney.

12 designates a pair of oppositely-disposed cleaning-rods riveted at their upper ends to the upper interior portion of wall 2 and extend downwardly in contact therewith a suitable distance, then extend inwardly a short distance at an angle of about forty-five degrees, and then downwardly to a point near the conical-form bottom 3, where they are united by a pair of brackets 13^a, secured at their opposite ends to conical bottom 3 and the under side of the transverse bar.

The heat on entering the outer casing from pipe 9 is deflected against the surface of wall 2 by an inner drum 14, comprising a cylindrical wall 15, a conical top 16, and a flat-bottom portion 17, which rests upon the transverse bar 13. The drum is of less diameter than wall 2 in order to leave an annular intervening space 18 for the passage of the products of combustion from pipe 9 to pipe 11.

19 designates a second pair of oppositely-disposed cleaning-rods paralleling the interior surface of wall 2, bottom 3, and the upper interior portion of pipe 9, and said rods are united at their upper ends by a transverse bar paralleling the under surface of lid 5 and forming a convenient handle 20. Rods 19 are secured at their upper terminals to the upper opposite sides of the drum by brackets 21 and at their lower ends to the lower opposite sides of the drum by brackets 22. By disconnecting pipe 11 from collar 6 access may be had to handle 20 through said collar, so that by grasping and rotating the handle nearly one-half a revolution in opposite directions the drum and cleaning-rods 19 will be carried therewith, so the latter will scrape the soot from the interior of wall 2 and bottom 3, while the stationary cleaning-rods 12 will scrape the soot from the sides and bottom of the drum. As bottom 3 is conical and the soot falling thereon will be agitated by the contacting portions of rods 19, the soot will fall through pipe 9 back into the stove, where it is consumed or may be removed in the usual manner. While stationary or in operation

the drum is held substantially concentric with the interior surface of wall 2 by the cleaning-
rods 12 and 19. The steep inclination of conical
top 16 affords but little opportunity for the soot
5 to lodge thereon; but as the greater portion of
the heat has been radiated before reaching
said top the accumulation of soot thereon will
have little or no effect upon the result.

Should the inner drum burn out or it be-
10 come necessary to make repairs to said drum
and the cleaning-rods, access may be readily
had thereto by removing lid 5.

In practice a slight space is preferably left
15 between the cleaning-rods and the drum and
casing to allow for any unevenness in the sur-
face of the latter caused by seams or failure
20 to make walls 2 and 15 perfectly cylindrical.

The modified form shown in Fig. 4 shows
25 means for operating the inner drum from the
exterior of casing 1, and consists of a rod 23,
extending inwardly through an aperture 23^a
in the casing and pivotally secured at its in-
ner end to one of the cleaning-rods 19. The
drum is pivotally mounted on pins 24 25, se-
cured to bar 13 and a bar 20^a, respectively,
which latter is secured to the underside of lid
5. Pin 25 projects through a central aperture
in handle 20, and pin 24 projects upwardly
30 into a conical recess 26 in the central portion
of the drum-bottom 17. By thus pivotally
mounting the drum friction caused by contact
with cleaning-rods 12 is avoided.

From the above description it is apparent
35 that I have produced an apparatus which is
simple in construction, economical to manu-
facture, and thoroughly effective for the pur-
pose intended.

Having thus described my invention, what
I claim, and desire to secure by Letters Pat-
40 ent, is—

1. An outer casing, cleaning-rods secured
to the interior thereof, an inner drum loosely
45 supported upon the cleaning-rods and having
a bottom and side walls paralleling the latter,
and cleaning-rods secured to the inner drum
and paralleling the inner surface of the outer
drum.

2. An outer casing, supporting-legs secured
thereto, cleaning-rods secured to the interior
50 of the outer casing, an inner drum loosely sup-
ported upon the cleaning-rods and having a
bottom and side walls paralleling said clean-
ing-rods, and cleaning-rods secured to the in-

ner drum and paralleling the inner surface of
the outer drum.

3. An outer casing, a removable lid for clos-
ing the upper end thereof, cleaning-rods se-
cured to the interior of the outer casing, an
inner drum loosely supported upon the clean-
ing-rods and having a bottom and side walls 60
paralleling the cleaning-rods, and cleaning-
rods secured to the inner drum and paralleling
the inner surface of the outer drum.

4. An outer casing comprising a cylindrical
wall, a conical-form bottom portion, and a lid 65
closing the top thereof, in combination with a
pair of cleaning-rods secured to the interior
of the casing, an inner drum loosely support-
ed upon the cleaning-rods and having a bot-
tom and side walls paralleling the clean- 70
ing-rods, and cleaning-rods secured to the inner
drum and paralleling the inner surface of the
outer drum.

5. An outer casing, cleaning-rods secured
75 at their upper ends to the upper interior sur-
face of the outer casing and which extend in-
wardly and downwardly a slight distance from
the interior surface of said casing, a transverse
bar uniting the lower ends of the clean- 80
ing-rods, and an inner drum supported by the
transverse bar and having its side wall ar-
ranged adjacent to and parallel with the clean-
ing-rods.

6. A cylindrical outer casing, an inner drum
loosely supported therein, cleaning-rods se- 85
cured to the drum and arranged adjacent to
and parallel with the inner surface of the wall
and bottom of the casing, and a transverse
handle uniting the upper ends of the clean- 90
ing-rods.

7. An outer cylindrical casing, a transverse
bar suitably secured therein, a drum located
within the outer casing and comprising a cy-
lindrical wall, a conical top and a flat bottom
95 portion which latter rests upon the transverse
bar; cleaning-rods secured to the drum and
paralleling the adjacent interior surface of the
wall of the outer casing, and a handle for op-
erating the drum and the cleaning-rods.

In testimony whereof I affix my signature in
the presence of two witnesses.

ENOCH BARNUM.
